GAME PIECE

Alan H. Ferber, 2264 La Granada, Hollywood, Calif.

Filed Feb. 5, 1963, Ser. No. 73,446

Term of patent 14 years

(Cl. D34—5)

FIG. 1 is a perspective view of a game piece showing my new design wherein the fanciful surface features represent an angel;

FIG. 2 is a perspective view of the opposite side of the angel shown in FIG. 1;

FIG. 3 is a perspective view of my game piece wherein the fanciful surface features represent the devil; and

FIG. 4 is a perspective view showing the opposite side of the devil of FIG. 3.

The essential features of my design reside in a game piece comprising a generally spherical head on a gen-

erally frusto-conical body, the head having fanciful surface facial features and the body having fanciful surface representations, all substantially as shown.

I claim:

The ornamental design for a game piece, substantially as shown and described.
